Des. 223,753
Patented June 6, 1972

223,753

VEHICLE TIRE CARRIER ACTUATING LEVER

Bob J. Seals, 8324 NW. 33rd,
Oklahoma City, Okla. 73123

Filed Mar. 20, 1970, Ser. No. 21,991

Term of patent 14 years

Int. Cl. D12—16

U.S. Cl. D14—6

FIG. 1 is a perspective view of the invention;
FIG. 2 is a front elevation of the invention;
FIG. 3 is a top plan view of the invention;
FIG. 4 is a rear view of the invention;
FIG. 5 is a bottom view of the invention;
FIG. 6 is a first end view of the invention; and
FIG. 7 is an opposite end view of the invention.

I claim:

The ornamental design for a vehicle tire carrier actuating lever, and the like substantially as shown.
